Patented Jan. 9, 1917.

UNITED STATES PATENT OFFICE.

HARRY E. CAMPBELL, OF NEW YORK, N. Y.

METAL WINDOW FRAME AND SASH.

1,211,913.

Specification of Letters Patent. Patented Jan. 9, 1917.

Application filed July 1, 1916. Serial No. 106,995.

To all whom it may concern:

Be it known that I, HARRY E. CAMPBELL, a citizen of the United States, residing at New York, in the county of New York and State of New York, have invented a certain new and useful Improvement in Metal Window Frames and Sashes, of which the following is a specification.

The invention relates to window-frames of metal, and consists in the construction of the upper rail of the sash and of the lintel, whereby by reason of the closing of the sash elastic weather-tight joints are formed between said sash rail and said lintel, which joints may be wholly inclosed within said lintel.

In the accompanying drawings—Figure 1 is an elevation of an upper corner of a window-frame and sash, illustrating my invention applied to the box lintel and upper sash rail. Fig. 2 is a section on the line α , α of Fig. 1.

Similar numbers of reference indicate like parts.

1 is a lintel of closed box shape, having its sides and top preferably integral. On the lower edge of the rear side is a horizontal flange 2, to which is bolted a plate 3 which covers the opening in the lintel bottom. Said plate may also be bolted to a transverse partition supporting bar 4 disposed within the lintel and resting on the bottom thereof. The outer longitudinal edge of plate 3 is bent upwardly to form an inclined flange 5. An angle bar 6 is secured to the inner face of the opposite side of the lintel, and has its edge bent upwardly to form an inclined flange 7, similar to flange 5, the two flanges converging toward one another.

The lintel 1 is supported in the window-frame by hollow jambs, one of which is shown at 8. In said jambs are vertical slots which receive guide plates 9 laterally extending on each side of the sash side rails formed by the bars 10, 10^a.

The upper sash rail is formed of two metal bars 11, 12 between which the pane 13 is received. Bar 11 is bent at right angles to extend over the top of the pane, and then forms a vertical extension plate 14. Bar 12 is secured, as by electric welding, to the extension plate 14 which extends

upwardly beyond the bar 12. When the sash is in raised position, said extension plate 14 enters between the flanges 5, 7 within the lintel, which form substantially a spring clip, producing tight joints on opposite sides of said extension plate. It is to be observed that these joints are wholly inclosed within the box lintel 1, and that the upper rail extension plate 14 being tightly grasped by the resilient flanges 5, 7, no rattling of the sash at said joints is possible.

I claim:

1. A window-frame of metal, comprising a lintel, having a longitudinal opening in its bottom, and within said lintel two separated resilient flanges on opposite sides of said opening and inclined toward one another, and a sash having on its upper rail a longitudinal vertical extension plate entering between said flanges, when said sash is in closed position.

2. A window-frame of metal, comprising a lintel, a sash having its upper rail formed of two bars united and receiving the pane between them, one of said bars being flat, and the other bar being bent twice to form a shoulder and a vertical portion extending upwardly from said shoulder and beyond the upper longitudinal edge of said flat bar, and two upwardly extending separated resilient flanges on said lintel receiving said vertical portion of said sash plate and resiliently engaging both sides thereof when said sash is in closed position.

3. A window-frame of metal, comprising a hollow lintel, having an opening in its bottom, a cover plate for said opening having on one longitudinal edge and within said lintel an inclined resilient flange, an angle plate secured to the front wall of said lintel having a resilient flange also within said lintel and inclined toward said first-named flange, and a sash having on its upper rail an extension plate entering between and in contact with said flanges, when said sash is in closed position.

In testimony whereof I have affixed my signature in presence of two witnesses.

HARRY E. CAMPBELL.
